UNITED STATES PATENT OFFICE

HARRY A. ATWATER, OF KANSAS CITY, MISSOURI

SELF RELIGHTING PILOT LIGHT FOR GAS BURNERS

Application filed August 26, 1929. Serial No. 388,445.

The present invention relates to pilot gas lighting devices for gas burners, and the primary object in view is to provide an improved construction of this character not only fulfilling the gas lighting function in an efficient manner, but also serving to safeguard the pilot lighting flame and effectively shielding the same and preventing it from becoming extinguished.

With the foregoing object in view, the invention comprises a gas lighting pilot construction in which the pilot flame is presented in its most efficient lighting relation to the main burner orifice, that is directly opposite the orifice and in the principal zone of combustion, while means is furthermore provided for maintaining a shielded zone for the pilot flame, together with flame-propagating means for maintaining the pilot flame constantly lighted in said shielded zone and thus effecting a perpetual relighting action between said zone and the pilot flame orifice and restoring the flame at the latter point as often as it may be caused to recede in the direction of the said shielded zone.

It is also sought to provide a burner construction having said improved pilot lighting device and including also a protective screen structure acting to shield the combustion zone around the principal burner orifice and preventing any explosive or backfiring action in the direction of the exterior of the burner.

With the foregoing general objects in view, as well as various minor features of improvement as will appear in the course of the detailed specification, the invention will now be described by reference to the accompanying drawings illustrating one form of burner construction which I have devised for embodying the proposed improvements, after which those features and combinations deemed to be novel will be set forth and claimed.

In the drawings—

Figure 1 is a side view (with parts broken away) showing a gas burner construction fitted with a pilot gas lighting device constructed in accordance with the present invention; and

Figure 2 is an elevation showing the interior or burner end of the same.

In gas burner practice, where the flow of gas to the burner is regulated in accordance with the temperature requirements for which the burner is operated, a pilot gas lighting device is required for relighting the main gas flame as often as this has been extinguished and requires to be relighted, and the principal difficulty in such pilot lighting operation arises when there is more or less abruptness in the variation of the main gas flow to the burner, inducing strong draft conditions which tend to extinguish the pilot lighting flame. In installations where the chimney flue is also connected directly to the burner unit, the influence of strong or gusty winds also aggravates the difficulty of maintaining the pilot flame constantly lighted.

Many expedients have been employed to overcome the difficulty which thus characterizes pilot lighting devices, such as to locate the pilot element in a dead pocket somewhat removed from the main burner orifice, in order to dampen the suctional action tending to extinguish the flame. However, such constructions are also objectionable insofar as they delay ignition on account of the remoteness of the pilot flame from the main burner orifice, thereby incurring danger of explosive ignition, sometimes strong enough to blow open the fire door.

Such a condition is fully as objectionable if not more so, than the one sought to be remedied, that of the tendency of the pilot flame to become extinguished and hence the desideratum in view is a combination of features in which the pilot flame may be left in its most efficient relation to the burner orifice for ignition purposes, and at the same time be so shielded from draft influences as to prevent the lighting flame from being put out under even the most severe draft conditions to which the installation might be subjected.

I achieve these results by means of a burner and pilot lighting device combination in which the pilot flame orifice is presented directly opposite the burner orifice, together with pilot flame propagating means commu-

nicipating with a shielded pilot flame zone and serving to constantly restore the pilot flame at the pilot orifice as often as the pilot flame is caused to recede.

- 5 Referring now to the drawings in detail, this illustrates the improvement as embodied in connection with a burner structure comprising a casing or housing 5 equipped with an adjustable face plate 6 for draft regulating purposes, the opposite end of the casing or housing 5 being fitted with a casting 7 formed with a plurality of burner openings 8 within which are positioned the various tips 9 of the burners, having the main burner orifices 10 as shown in Figure 2. These burner elements are supplied with the necessary gas flow from a header 12 to which the gas supply is conducted by a pipe 14 as shown in Figure 1.
- 20 The pilot lighting structure comprises a gas tube 16 extending across the face of the casting 7 and formed with a longitudinal flame propagating slot 17, and branch pilot flame slots 18 located opposite each of the burner tips 9 and orifices 10, as shown in Figure 2. The pilot tube 16 is carried backward alongside the casing or housing 5, where it is fitted with a cup-shaped or hood element 20 provided with a plurality of openings or perforations 21 surrounding the extreme outer end of the flame propagating slot 17. This outer end of the pilot tube 16 and its hood element 20 are further protected by means of a casing member 22 attached to the housing 5 by the screws 23.

Outside the casing member 22 the pilot tube is fitted with an air premixing element 25, and a suitable valve 26 as shown in Figure 1.

- 40 Inside the casing or housing 5 a wire mesh screen element 30 is provided for shielding the space back of the combustion zones around the tips of the burners 9, this being for the purpose of preventing any flare back tending to follow the ignition of the gases around the burners for any cause, and thus providing an additional factor of safety for the burner as well as further protection against extinction of the pilot lighting flame.

- 45 The construction as thus described provides a pilot flame orifice so located as to project a lighting flame directly into the path of gas issuing from the several burner orifices 10, and these pilot flame orifices are all in communication with the slot 17 constituting the flame propagating means extending from the shielded zone at the outer end of the slot 17 within the hood member 20.

- 50 As often, therefore, as the jets of flame are snuffed out at any one or more of the slots 18, and the pilot lighting flame caused to recede in the direction of the hood element 20, the flame is constantly relighted and restored as it is propagated back along the slot 17 to each one of the orifices 18, in an obvious manner.

In further explanation of this operation, it may be said that the critical point at which the pilot flame tends to become extinguished is upon the abrupt shutting off of the flow of gas to the burner elements 9, and not at 70 the times when the gas flow to the burners is renewed. That is to say, on stopping of the gas flow to the burners, the momentary excessive draft action within the burner tends to snuff out the pilot flame, so that this momentary extinction of the pilot flame occurs at an interval when the function of the pilot is not needed; during this interval, the pilot flame is however left still burning at the outer end portion of the slot 17 and within the hood 80 element 20, and as the draft action becomes neutralized by the inflow of atmospheric air the gas along the slot 17 is relighted and the pilot flames are restored at all the orifices 18 in readiness to reignite the gas jets from 85 the several burner orifices 10, as soon as the main gas flow is restored to the burner.

The hood structure 20 and protective box or casing 22 afford a complete shielding or protective action for the outer zone of the 90 pilot relighting flame, the function of the perforations 21 of the hood 20 being to maintain the pilot relighting flame well back inside the hood element regardless of the sudden or excessive draft or pressure conditions which might be created in the main firebox space in front of the burner openings 8.

It is found by experiment that with the protective assembly shown, for shielding the outer end of the pilot relighting flame, no 100 firebox draft conditions are apparently possible of development which may result in complete extinction of the relighting flame of the described pilot structure.

The premixture of the air and gas by 105 means of the fitting 25 results in a pilot flame which is of the true Bunsen type, always burning clear and blue and eliminating the deposit or carbon upon the pilot device. This feature however is not essential, since a plain 110 gas flow without air premixing may be used, depending upon the requirements of the particular installation. The various component parts of the assembly may also be of any suitable or preferred material, such as metal, 115 lava material, or other refractory compositions, as may be found necessary or desirable.

It will thus be apparent that I have devised a practical, efficient as well as highly adaptable arrangement and construction, for fulfilling the desired purposes of the invention. The pilot lighting arrangement affords the maximum efficiency as regards the burner ignition, and with proper installation of the pilot tube, and shielding of the outer end of 120 the pilot flame transmission slot, any danger of complete extinction of the relighting flame is effectually eliminated. It is also to be noted that the arrangement of the pilot structure is one which may be adapted to any 125 130

particular design of burner, by simply carrying the pilot tube alongside the various burner openings, and providing a pilot jet orifice opposite said openings and thus establishing communication from said orifice to the protected zone of the pilot flame, as in the illustration here given.

While I have illustrated and described one practical form of construction for embodying these improvements, I desire to be understood as reserving the right to make all changes or modifications which may fairly fall within the scope of the following claims.

Having thus described my invention, what I claim and desire to secure by Letters Patent is:

1. A pilot lighting construction comprising, in combination with a burner, a pilot gas tube having a pilot flame orifice in proximity to the burner, and also formed with a continuous flame propagating slot extending from said pilot orifice to a point remote from the burner orifice, and a hood member provided with air openings surrounding the tube at the outer end of said slot for shielding the pilot flame.

2. A pilot lighting construction comprising, in combination with a burner, a pilot gas tube having a pilot flame orifice in proximity to the burner, and also formed with a continuous flame propagating slot extending from said pilot orifice to a point remote from the burner orifice, and a hood member surrounding the outer end of said slot with the open end of said hood member presented in the direction of the inner portion of the slot.

3. A pilot lighting device for gas burners comprising a tube provided with a pilot flame orifice and with a longitudinal slot extending from the orifice to a point remote therefrom, a perforated flaring hood surrounding the outer end of said slot, and a housing enclosing said hood and extending in the direction of said orifice.

4. A pilot lighting device for gas burners comprising a tube provided with a pilot flame orifice and with a flame propagating structure extending from said orifice to a point remote therefrom, a hood structure shielding the outer end of said flame propagating structure, and flaring in the direction of said orifice, and an air premixing device associated with the tube adjacent to said hood structure.

5. In witness whereof I hereunto affix my signature.

HARRY A. ATWATER.
